UNITED STATES PATENT OFFICE.

FRANK P. SAWDERS AND JAMES G. MURRAY, OF PITTSBURGH, PENNSYLVANIA.

SPRING-SHACKLE.

1,352,633.

Specification of Letters Patent. Patented Sept. 14, 1920.

Application filed December 2, 1919. Serial No. 341,951.

To all whom it may concern:

Be it known that we, FRANK P. SAWDERS and JAMES G. MURRAY, citizens of the United States, residing at Pittsburgh, in the county of Allegheny and State of Pennsylvania, have jointly invented a new and useful Improvement in Spring-Shackles, of which improvement the following is a specification.

Our invention relates in particular to shackles for the springs of motor propelled vehicles.

Our invention has for its objects, to provide a shackle that will maintain positive lubrication at the point of suspension, that will not require attention at frequent intervals, that will not be liable to clog, and that will be simple in construction.

With the above objects in view, our invention consists in certain features of construction and arrangement of parts as will be hereinafter more specifically described and particularly set forth in the appended claims.

In the accompanying drawings we have shown an embodiment of our invention, wherein—

Figure 1 is a side elevation thereof and Fig. 2 an end elevation of the same partly in section on the line X—X of Fig. 1.

The device is in the form of a bifurcated member, from the body portion 1 of which projects the branches or lugs 2 in parallel relation, which are adapted for the reception of the end of a suitable spring, said spring end to be loosely mounted on and connected thereto by a suitable pin passing through the spring eye and lug openings 3. The extremities of these lugs are slotted 40 and bolt holes 4 formed therethrough at right angles to said slits, said openings being intended for the reception of bolts to secure the pins in place. The body portion 45 of the device is hollow, to form the oil reservoir leaving a space 5 at the lower end about the openings 6, within which openings is tightly fitted the sleeve bearing 8 having feed openings 9 therein, said body being disposed at an angle and projecting to one side, there being a threaded opening 7 in the top thereof for connecting an oil cup or other lubricating supply means thereto.

The shackle being applied to the rod or pin upon which it operates, and the cham-

ber filled with the lubricant, which surrounds the bearing sleeve 8, it is evident that the bearing surface between the sleeve and rod or pin upon which it is supported, will be fully lubricated by the gravitating pressure of the lubricating body in the chamber, fed thereto through the ports 9. By projecting the body of the shackle outwardly at an angle it is then in a position where it may readily be charged.

Having thus shown and described our invention, what we claim is—

1. A spring shackle for the purpose set forth, comprising a bifurcated member the forked portion of which is adapted to receive the end of a spring, the body portion thereof below the fork being hollow to form a lubricating reservoir, and a bearing sleeve extending through the base of said reservoir and adapted to fit over a supporting member, said sleeve being provided thereabout with spaced feed openings, said reservoir surrounding said sleeve and communicating therewith through said openings, the major portion of said reservoir being disposed above said sleeve so that a lubricant therein will have a gravity feed through said openings.

2. A spring shackle for the purpose set forth, comprising a bifurcated member the forked portion of which is adapted to receive the end of a spring, the body portion thereof below the fork being hollow to form a lubrication reservoir the upper portion of which projects from between the fork legs and provided with a charging opening, and a fixed bearing sleeve extending through the base of said reservoir and adapted to fit over a supporting member, said sleeve being provided thereabout with spaced feed openings, said reservoir surrounding the sleeve and communicating therewith through said openings, the major portion of said reservoir being disposed above said sleeve so that a lubricant therein will have a gravity feed through said openings.

In testimony whereof, we have hereunto signed our names in the presence of two subscribing witnesses.

FRANK P. SAWDERS.
JAMES G. MURRAY.

Witnesses:

R. S. HARRISON,
A. R. FRIEL.
